UNITED STATES PATENT OFFICE

WILLIAM E. KERR, OF DES MOINES, IOWA

LAUNDRY APPLIANCE

Application filed June 11, 1927. Serial No. 198,223.

The object of my invention is to provide a laundry appliance of simple, durable and inexpensive construction in the nature of a support, and means mounted on the support for adjustment therearound, which means are adapted to support tubs, baskets and the like for the convenient handling of clothes during laundering operations.

A further purpose of my invention is to provide such a support upon which tub and basket supporting members may be adjustably and detachably mounted.

Another object is to provide in such a structure, convenient conduit means for water and gas pipes.

With these and other objects in view, my invention consists in the construction, arrangement and combination of the various parts of my laundry appliance, whereby the objects contemplated are attained, as herein-after more fully set forth, pointed out in my claim, and illustrated in the accompanying drawings, in which:

Figure 1 is a side elevation of a laundry appliance embodying my invention, parts of the device being shown in section and parts being broken away.

Figure 2 is a sectional view taken on the line 2—2 of Figure 1.

Figure 3 is a horizontal, sectional view taken on the line 3—3 of Figure 1.

Figure 4 is an enlarged, plan view of the top of the device; and

Figure 5 is an enlarged sectional view taken on the line 5—5 of Figure 4.

My device comprises a support and adjustable tub holding means thereon adapted to be placed on the floor of a laundry room for conveniently carrying on various washing operations.

In the drawings herewith, I have used the reference numeral 10 to indicate generally a laundry floor having the sewer drain 11.

My laundry appliance includes an upright tubular post 12 forming part of the main support. The tubular post member 12 is provided with the flanged piece 14, which may be anchored to the floor in any suitable way.

At its upper end, the post member 12 has a tubular extension 12^a of smaller diameter

than the lower part of the post member. The post member 12^a has an annular shoulder 12^b adjacent to the lower part of the extension 12^a.

Hung on the extension 12^a, I provide three 55 swinging supporting devices indicated in Figure 2 at A, B and C.

The device A for example comprises an annular ring 16 welded or otherwise secured to a short arm 17 extending from a smaller 60 ring 18.

The device C comprises an annular ring 20 within which is a spider or the like 21. The ring C may be similar to the ring A and have a wire mesh welded in it to extend thereacross. 65 (See Figure 3.) Projecting from the ring 20 is an offset arm 22, as seen in Figures 1 and 3, terminating in a smaller ring 24.

Resting on the shoulder 12^b is a suitable washer 26 above which is placed the ring 24 70 for thus mounting the supporting element C on the post member 12. Similarly above the ring 24 is a similar washer 26 above which rests the ring 18 of the supporting element A.

The supporting element B is similar to the 75 supporting element A and comprises the large annular ring 16^a and the smaller ring 18^a connected by an offset arm 17^a.

Above the ring 18 is another washer 26 and above that is the ring 18^a of the support B 80 and resting on the ring 18^a is still another washer 26.

The upper portion of the main upright support comprises an upright, tubular member 85 having a bell-shaped extension 32 at its lower end, which receives the upper end of the extension 12^a, as shown in Figure 1, and is fastened thereto by means of set screws or the like 34.

It will be seen that the supporting elements 90 A, B and C may be swung around the post member 12 as may be desired.

A gas pipe 38 may be extended under the floor and then upwardly through the pipe 12 and into the tubular post 12^a, as shown in 95 Figure 1. The gas pipe is then preferably extended through the wall of the post member 12^a, and provided with a burner 40. A controlling valve 42 may be provided in the gas pipe 38.

Hot and cold water pipes 44 and 46 may be extended upwardly through the post members 12 and 30 to a mixing chamber 48 mounted on top of the post member 30 and having the ordinary mixing valves 50 and 52.

5 The mixing chamber 48 is best illustrated in Figure 5 of the drawings in which the pipes 44 and 46 are shown in communication with cavities 45 and 47. Turning the handles 50 and 52 operates the valve plugs 51 and 53 for controlling the flow of hot and cold water to the mixing chamber 55.

10 A discharge pipe and spout 54 is pivoted to the mixing chamber 48, so as to swing around the upright post. The spout 54 discharges the water from the mixing chamber 55.

15 Preferably the upright post member 30 is provided at its upper end with an annular flange 56, on which rests an annular shelf 58. A top or cover member 60 has a flange 62 resting on the shelf 58. The flanges 62 and 56 and the shelf 58 are fastened together as by bolts 64.

20 25 In connection with the upright supporting post and the members A, B and C, I preferably provide for the members A and B, tubs 68 having their lower ends adapted to be received in the rings 16 and 16^a, as illustrated 30 for instance in Figure 1.

The tubs 68 are preferably provided at their bottoms with drain tubes 70 with discharge cocks 72.

It will be seen that in the practical use of 35 my improved laundry appliance, the upright supporting device may be placed at any desired point on a laundry floor in a basement or otherwise.

40 Preferably the device is so arranged that the contents of the tubs 68 can be discharged directly to the drain sewer 11. (See Figure 1).

45 When the device has been assembled, the water in one tub can be readily heated from the burner 40 when the tub is swung to position above the burner.

Two tubs are available, which can be placed in various positions with relation to each other around the upright support.

50 A basket can be mounted on the spider 21 and ring 20 for use in connection with either of the tubs.

The shelf 58 may be used for soap or washing implements.

55 The discharge pipe 54 may be swung around for use in any adjusted positions of the members A and B and the tubs supported thereby.

60 It will readily be seen that with a device of this kind, tubs can be filled with water, the water heated and used, and the tubs swung to various positions and the water discharged therefrom without the necessity for lifting any tubs or carrying any water.

65 The positions of the tubs may be readily changed to suit the requirements of the laun-

dry where the device is in use with a minimum of heavy labor.

A pair of Y-shaped supports 74 are preferably mounted on the discharge pipe 54 for supporting a laundry stick. 70

This device is particularly advantageous for use in domestic laundries. As will be readily seen, it has a great many conveniences for saving time and work.

75 The water pipes 44 and 46 may come from above and be connected to the mixing chamber 48 instead of from below. To provide for this, bosses 48^a are formed on the mixing chamber 48 to receive the pipes 44 and 46. The bosses 48^a or the bottom of the mixing chamber 49 may be plugged with pipe plugs 49 depending on whether the pipes come from below or above.

An opening 51 is provided for the gas pipe 38 if it comes to the appliance from above. 85

The parts may be made of any materials suitable for the purpose, and it is not my intention to limit myself to the exact structure herein disclosed, but it is my purpose to cover by my claim any modified forms of structure 90 or use of mechanical equivalents, which may be reasonably included within their scope.

I claim as my invention:

In a laundry appliance of the class described, an upright support, a plurality of 95 supporting devices each independently rotatably mounted on said support and adapted to be independently swung on the support, a burner mounted on said upright support below the devices, whereby a tub on any supporting device may be readily moved to position above the burner and the other supporting devices may be moved to different positions with relation to each other and the one over the burner. 100

Des Moines, Iowa, March 22, 1927.
